CLAIM

The ornamental design for a luggage carrier for motor vehicle, as shown and described.

DESCRIPTION

FIG. 1 is a perspective view of a luggage carrier for motor vehicle showing my new design;

FIG. 2 is a front view thereof;

FIG. 3 is a rear view thereof;

FIG. 4 is a right view thereof;

FIG. 5 is a left view thereof; and,

FIG. 6 is a top view thereof.

The broken lines in the drawings illustrate portions of the luggage carrier for motor vehicle that form no part of the claimed design.
